WINFIELD P. PEMBROKE, OF ROCHESTER, NEW YORK.

CARBURETER.

1,241,014.

Specification of Letters Patent. Patented Sept. 25, 1917.

Application filed March 2, 1915. Serial No. 11,572.

To all whom it may concern:

Be it known that I, WINFIELD P. PEMBROKE, of Rochester, in the county of Monroe and State of New York, have invented 5 certain new and useful Improvements in Carbureters; and I do hereby declare the following to be a full, clear, and exact description of the same, reference being had to the accompanying drawings, forming a 10 part of this specification, and to the reference-numerals marked thereon.

My present invention has for its object to provide a carbureter for explosive engines containing certain improvements, 15 whereby the auxiliary supply of air is regulated to produce a suitable mixture at all motor speeds and in which the additional supply of air and fuel required for strong motor demands is automatically derived and 20 controlled by the partial vacuum created in the mixing chamber of the carbureter by the suction of the engine, the arrangement of the parts being such that a constant ratio is maintained between the supplies of 25 fuel and air at all speeds of the engine and at various openings of the throttle valve. To these and other ends the invention consists in certain improvements and combinations of parts, all as will be hereinafter 30 more fully described, the novel features being pointed out in the claims at the end of the specification.

In the drawings:

Figure 1 is a side elevation of a carbureter 35 showing one embodiment of my present invention;

Fig. 2 is a cross sectional view thereof; Fig. 3 is a top plan view;

Fig. 4 is a vertical sectional view taken 40 on the line 4^x—4^x of Fig. 1, and

Fig. 5 is an enlarged sectional view illustrating the operation of the auxiliary air valve.

Fig. 6 is a detail perspective view of the 45 adjustable gate, or valve, controlling the main air inlet passage.

Similar reference numerals throughout the several views indicate the same parts.

My present invention provides a carbureter utilizing two different fuel inlets 50 which are so arranged in conjunction with the air inlets that high power may be obtained from the engine at certain times and at others very slow or idling thereof may 55 occur and between these extremes an even

and steady operation of the engine obtained. The fuel supply is obtained from two different discharge nozzles, one furnishing the required amount of liquid fuel or gasoline to produce the comparatively rich mixture 60 required when the engine is working at low and intermediate speeds and the second nozzle which operates conjointly with the one first mentioned and produces the fuel which is to be mixed with the greater volume 65 of air which rushes through the carbureter when the engine pistons reciprocate with greater velocity.

In illustrating my invention I have shown a carbureter comprising the shell or casing 70 1 forming the mixing chamber A and the float chamber B arranged at one side thereof. The mixing chamber is provided at its upper end with the usual butterfly valve or throttle 2 carried on the shaft 3 provided 75 at one end with the crank arm 4. The lower end of the chamber A is closed by the bottom 5 and arranged at a point slightly above the latter is the main air inlet 6 from the upper edge of which is an inwardly and downwardly extending wall 7 arranged to direct the incoming currents of air downwardly in proximity with the bottom 5 which is concave to form a trap or receptacle for the liquid fuel. At the lower end 80 of the partition 7 is an adjustable gate or valve 8 which can be rotated to vary the width of the sheet of air passing beneath the partition and to regulate the proximity of said air currents to the surface of the liquid 85 contained in the bottom of the mixing chamber, or if desired the gate may be adjusted to cause said air currents to pass through the body of the trapped liquid. The adjustment of the gate in the first instance 90 depends principally upon the gravity of the fuel and the average atmospheric conditions of the locality in which the carbureter is employed. This valve or gate 95 extends transversely of the carbureter casting and is journaled in the side walls thereof, as shown in Figs. 2 and 4, one of its ends being elongated to form a hub or projection, on which the dash pot 30 is preferably supported and held by set screw 30^b. 100

The main fuel inlet nozzle of the carbureter is formed by the orifice 9, the area of which is controlled by the needle valve, or metering pin, which carries at its outer end a threaded nut 11, coöperating with a. 110

bracket or outer bearing 12, the pin being held in its innermost position by a coil spring 13 arranged between said bracket and a collar 14 on the pin. The latter carries a 5 pivoted cam member 15, which, when rotated, contacts with the wall of the shell 1 and causes the pin to be retracted to open the orifice 9 and permit the unrestricted flow of the fluid into the mixing chamber A.

10 The ordinary demands of the engine, to which the carburetor embodying my invention is applied, are satisfied by the quantities of liquid fuel entering the mixing chamber through the orifice 9 and the air 15 entering said chamber through the main inlet and, in the first instance, these parts are proportioned, or adjusted, for the usual range of low speed operations and a further feature of my invention is to provide means 20 for automatically regulating the auxiliary supplies of fuel and air, which become necessary at higher engine speeds or strong motor demands. As the requirements of an engine increase during acceleration in speed the additional quantity of fuel required is supplied by the orifice 9 and a satisfactory carburation of the air admitted through the main air inlet 6 is obtained up to a given point. However, after that point is reached 25 30 where the partial vacuum draws in fuel in excess of that required to carbure the maximum volume of air admitted through the inlet 6, it is essential that an auxiliary supply of air should be provided to take care of the excess fuel produced by the ever increasing suction. At the point where a balance occurs 35 between the air admitted through the main air inlet 6 and the fuel admitted through the primary nozzle 9, further motor demands, or increased engine speed, necessitates the addition of a further supply of fuel 40 coupled with a further increase in the supply of air.

By my present invention I have accomplished the requirements above stated 45 through the instrumentality of an auxiliary air and fuel valve mechanism, the movement of which is controlled by the partial vacuum created in the mixing chamber A, 50 these parts being so arranged that no aspirating effect on the auxiliary fuel supply nozzle is produced until after said air valve has admitted the quantity of air first required to produce the balanced effect above 55 referred to in conjunction with the operation of the primary fuel inlet.

Further describing the valve mechanism it may be said that it comprises an adjustable member arranged in the air inlet passage 60 relatively to the fuel inlet and controls the flow of air currents in the passage at the forward or inlet side of said nozzle and their exit at the other side of said nozzle. This valve is also so constructed that during its 65 initial opening movement no aspirating

effect is produced to draw in the fuel, the outlet in rear of the nozzle being then the restricted portion, but after the valve has reached a predetermined point in its movement the inlet in front of the nozzle, becomes the restricted portion and the partial vacuum created in the air inlet passage then exerts its influence to draw fuel into the mixing chamber.

In illustrating this portion of my invention I have shown the valve mechanism in the form of an oscillatory cylinder 20 having a transverse aperture defined by the walls *a* and *b*, and located in an air passage 21 terminating in the mixing chamber A at 70 a point below the throttle valve 2. The inner end of the passage at its upper side either ends at or is provided with a shoulder indicated by the point *c* and with which co-operates the inner edge or lip *a'*, of the wall 75 *a*, of the valve slot. The inner face of one of the walls of the air passage is curved, as shown at 23, and co-operates with the edge *b'* of the wall *b*, of the valve slot. The relative positions of the stationary portions *c* 80 and 23 and movable lips *a'* and *b'* of the valve are such that when the valve is normally closed, as shown in Fig. 2, there is a slight opening at a point indicated by *o'* (Fig. 5), which prevents any suction whatever 85 being exerted on the high speed fuel nozzle 24 even should leakage occur around the valve cylinder 20. When the latter begins to open and the point *a'* leaves the shoulder *c* a corresponding movement of the 90 shoulder *b'* occurs in a direction away from the curved face 23 so that during a portion 95 of the opening movement of said valve a greater air space exists at the inlet portion of the air passage than at the exit end, so 100 that no aspirating effect is imparted to the fuel nozzle located in the air inlet.

This initial period of the opening of the valve is provided to supply the auxiliary air required, in addition to the air entering the 110 main air inlet 6, to form the proper carbureted mixture, and the valve 20 being automatically controlled this condition exists until the power demands of the engine reach the point where fuel must be supplied from 115 the auxiliary nozzle 24. The auxiliary air is supplied without additional fuel being added until the valve lips *a'*—*b'* reach a position indicated by the line *x*—*x* in Fig. 5. At about this position a change begins to 120 occur, by reason of the proportion of the parts, whereby the inlet portion of the air passage, extending between the lip *b'* and the curved face 23, becomes reduced in area 125 in proportion to the space between the shoulder *c* and lip *a'* which correspondingly increases in area. This effect transfers the point where the suction in the air passage becomes noticeable from a point behind to that in front of the auxiliary fuel inlet. 130

After this condition is established it continues during the further rotation, or opening movement, of the valve member 20 and by reason of the curved face of the wall 23, 5 the aspirating effect on the nozzle 24 continues even though greater volumes of air are admitted. The relative positions of the shoulders a' and b' are indicated in Fig. 5, by the reference characters $0^a-1^a-2^a-3^a-4^a$, and by $0'-1'-2'-3'-4'$, and the corresponding dotted lines which show the positions of the walls a and b at different points of adjustment of said valve member. 10 From the above described arrangement of elements it will be observed in the broad aspect of the invention, there is provided an air passage, in which a partial vacuum is maintained, with the walls of which co-operates a valve mechanism controlling the flow of air currents at opposite sides of the fuel inlet and that these elements themselves may be considered as a carburetor independently of the primary sources of air and fuel supply. At the first the maximum 15 restricted point or area in which the aspirating effect is produced lies in rear of the fuel inlet and upon the continued movement of the valve member this area is transferred to the inlet side of said nozzle, so that the partial vacuum created in said passage exerts 20 its influence to produce a condition causing the liquid fuel to be supplied in the desired quantity. When the aspirating effect begins to be produced by the restriction of the air 25 passage in front of the supply nozzle only a smaller quantity of fuel will be permitted to flow, but as the difference in pressure increases, due to stronger engine demands, and the valve member is opened further to admit 30 a greater volume of air, the area of the inlet passage, while being increased is also controlled by the shape of the curve 23, so that the restriction maintained is sufficient to produce an increased flow of fuel. 35 The movable valve member 20, shown in the present instance as being an oscillatory member, may be operated by any suitable means, but I prefer to control it automatically and to this end, I provide an operating 40 mechanism which is operated by the partial vacuum created in the carbureting chamber A of the carburetor. A simple means for accomplishing the object mentioned comprises a dash pot in the form of a cylinder 50 55 connected at its lower end by a passage 30^a leading into a port or opening 30^e extending through the hub of valve 8 into the casing 1, and provided with a piston 31 having a rod 32 pivoted to an arm 33 attached 60 to the end of the valve member 20. The upward movement of the piston 31 in the cylinder is limited by a collar 34, which permits the atmospheric pressure to act upon said piston, against the tension of a light spring 65 35, the strength of which is only sufficient to

hold the parts in their normal position, as shown in Fig. 1, with the valve member 20 closed, as shown in Fig. 2.

In mounting the dash pot 30 I preferably combine it with the air gate or valve 8, so that the slight oscillation which occurs, due to the rocking of the arm 33, will cause said primary air valve to be rotated slightly and permit an increase in the flow of air admitted through the main inlet 6. As will be observed from an inspection of Fig. 1, the dash pot 30 is mounted on the extension or hub of the valve 8, and these parts are provided with registering apertures 30^a and 8^a affording communication between the interior of the dash pot and the air passage leading into the main chamber, the passage 8^a being preferably made in the form of a slot at its outer end to permit the adjustment of the valve 8 in setting the parts in their operative positions in the first instance. 70 80 85

I claim as my invention:

1. In a carburetor, the combination with a casing forming an auxiliary air passage in which a partial vacuum is formed and an auxiliary source of fuel supply connected to said passage and adapted to discharge therein under the influence of said partial vacuum, of a single valve arranged to first open the air passage at a point in front of said fuel discharge a greater distance than it opens said passage in rear of the fuel discharge and subsequently upon the continued movement of the valve effect a reverse of the condition of the opening at said points. 90 95 100

2. In a carburetor, the combination with a casing forming an auxiliary air passage in which a partial vacuum is formed and an auxiliary source of fuel supply connected to said passage and adapted to discharge therein under the influence of said partial vacuum, of a single valve located in the passage and arranged to first permit the suction created by said partial vacuum to be exerted in rear of the point of fuel discharge and upon the continued movement of the valve to transfer the area at which the suction is created to a point in front of said fuel discharge. 105 110 115

3. In a carburetor, the combination with the walls of an auxiliary air inlet passage, in which a partial vacuum is formed, and an auxiliary fuel discharge nozzle extending and discharging transversely of the passage, of a revoluble valve member having an opening therein and co-operating with the passage walls at opposite sides of the nozzle to automatically transfer the point of aspiration from a point in rear of the nozzle to a point in front thereof. 120 125

4. In a carburetor, the combination with the walls of an auxiliary air passage in which a partial vacuum is formed and an auxiliary fuel discharge nozzle extending 130

and discharging transversely of the passage, of an oscillatory valve member having an opening therein coöoperating with said walls in front and in rear of said nozzle 5 and serving to alternately transfer the area of aspiration from one side of the nozzle to the other.

5. In a carbureter, the combination with the walls of an auxiliary air passage, one 10 of which is curved and in which a partial vacuum is formed and an auxiliary fuel discharge nozzle extending and discharging transversely of the passage, of an adjustable valve member having an aperture co- 15 operating with said walls and serving to alternately transfer the area of aspiration from a point at one side of the nozzle to a point at the other side thereof.

6. In a carbureter, the combination with 20 the walls of an auxiliary air passage, in which a partial vacuum is formed, one of said walls being curved and the other being provided with a shoulder, and an auxiliary fuel nozzle extending and discharging trans- 25 versely of the passage into the passage between said curved surface and shoulder, of a valve member coöperating with said surface and shoulder and operating to alternately shift the area of aspiration from one 30 side of the nozzle to the other.

7. In a carbureter, the combination with the walls of an auxiliary air passage, in which a partial vacuum is formed, one of said walls being curved and the other being 35 provided with a shoulder, of an oscillatory valve member provided with a transverse aperture, the walls of which coöperate with said curved surface and shoulder to shift the area of effective aspiration from one end 40 of the valve aperture to the other and an auxiliary fuel nozzle extending and dis-

charging transversely of the passage into the valve aperture.

8. In a carbureter, the combination with a casing having a mixing chamber in which 45 a partial vacuum is produced, an air valve, a cylinder connected thereto and communicating with said mixing chamber, a piston therein adapted to be operated upon the reduction of pressure in said chamber below 50 a predetermined point, of an oscillatory auxiliary air valve connected to said piston.

9. In a carbureter, the combination with a casing having a mixing chamber in which 55 a partial vacuum is produced, a pivoted cylinder having communication with the interior of the mixing chamber and a piston in said cylinder, of an auxiliary fuel and air supply mechanism connected to the piston and adapted to be opened by the movement imparted thereto upon the reduction of pressure in said mixing chamber below 60 a predetermined point and means for closing said valve when the pressure in said 65 chamber rises.

10. In a carbureter, the combination with a casing having a mixing chamber in which a partial vacuum is produced, a main air valve, a cylinder connected with said air 70 valve for moving the same and a piston movable in the cylinder and arranged to be operated upon the reduction of pressure in said chamber below a predetermined point, of an auxiliary fuel and air supply 75 mechanism operated by the movement of said piston.
